H. W. BARTOL.
STEAM TRAP.

No. 65,047.

Patented May 28, 1867.

Inventor:
Henry W. Bartol
D. C. Patent Office
his attorney.

United States Patent Office.

HENRY W. BARTOL, OF PHILADELPHIA, PENNSYLVANIA.

Letters Patent No. 65,047, dated May 28, 1867.

IMPROVEMENT IN STEAM TRAPS.

The Schedule referred to in these Letters Patent and making part of the same.

TO ALL WHOM IT MAY CONCERN:

Be it known that I, HENRY W. BARTOL, of the city of Philadelphia, in the county of Philadelphia, in the State of Pennsylvania, have invented a new and useful Improvement in "Steam Traps;" and I do hereby declare that the following is a true and exact description of the same, reference being had to the accompanying drawings, a part of this specification, in which—

Figure 1 is a sectional elevation of my steam trap.

Figure 2, a section of the same on xx .

Figure 3, a perspective view of the ring by means of which the metallic strip A_m is held in proper place inside the steam trap.

Figure 4 shows the metallic strip A in its full length.

The nature of my invention consists in a steam trap, which closes or opens by means of the contraction or expansion of an inside metallic strip, bearing a valve-seat, which sets on and closes the mouth of discharge pipe.

To enable others skilled in the art to make and use my invention, I will proceed to describe its construction and operation.

I construct an ordinary cylinder, A B A' B', which I set on the discharge pipe C, as shown in fig. 1 in M and N, said cylinder receiving the steam through D D' D' D in the usual way. Cylinder A B A' B' is provided at both inside ends with rings or bosses K and K, which are cut bevel on the top, as shown in R and R', figs. 1 and 3, thus forming a bevel-notch, where the end of spring A_m is to rest and be held. I cut a strip of spring brass, or any suitable metal, of a sufficient length to have it bent, as shown in fig. 1, when in proper place in cylinder A B A' B', and on the middle of said metallic strip A_m I attach valve S.

Now, when the steam will enter the cylinder, the expansion of metallic strip A_m will bring down valve S, which will then close opening E; and when the steam begins condensing, the metallic spring A_m will contract, and open the passage L, through which water of condensed steam, or water, will be admitted into discharge pipe C.

Having thus described and explained my invention, what I claim as my invention, and desire to secure by Letters Patent of the United States, is—

1. The arrangement of spring A in cylinder A B A' B', so that when the steam enters the cylinder the expansion of metallic spring A will close opening E, as and for the purpose described and set forth.
2. The spring A, held and secured in proper place by means of ring-bosses K and bevel-notch R, as and for the purpose described and set forth.

HENRY W. BARTOL.
